UNITED STATES PATENT OFFICE

RICHARD H. BAIR, OF CAMP HILL, PENNSYLVANIA

PENCIL SHARPENER

Application filed April 18, 1932. Serial No. 605,891.

This invention relates to new and useful improvements in pencil sharpeners and has for an object to provide a pencil sharpener including a support and a sharpening means mounted on and eccentric to said support and adapted to receive an end of a pencil and sharpen the same on being rotated about the support by the pencil as a crank.

Another object is to provide a pencil sharpener as stated and including a mounting for the sharpening means whereby said means is held against rotation about its own axis but may rock sideways to prevent breaking of the lead of the pencil by lateral cramping of the pencil during the sharpening operation.

A further object is to provide a device having the characteristics described and which is efficient in operation and of simple and inexpensive construction whereby it may be manufactured and sold at a relatively low price.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a top plan view of a pencil sharpener in accordance with the invention, part of the cover being broken away;

Fig. 2 is a view partly in side elevation and partly in section showing the interior mechanism;

Fig. 3 is a view with the cup or case and the cover sectioned as along the line 3-3 of Fig. 1 and showing a pencil being sharpened;

Fig. 4 is an enlarged plan view illustrating the mounting for the sharpening means;

Fig. 5 is a detailed sectional view along the line 5-5 of Fig. 4; and

Fig. 6 is a bottom plan view of the sharpening means.

Referring in detail to the drawing, the improved pencil sharpener as here disclosed

includes a cup or case member 7 comprising a bottom wall 8 and preferably a circular side wall 9, the cup being open at its upper end. Arranged centrally of the bottom wall 8 and extending outwardly and upwardly therefrom is a post or support 10 hollow in its upper end portion as shown in Fig. 3 and terminating at a point just above or outwardly of the upper or outer edge of the side wall 9 of the case.

A cover 11 normally closes the upper or open end of the cup or case 7 and this cover as here shown is in the form of a disc provided centrally with a pin or rivet 12 rigid with the cover and of a length and diameter to be received in the hollow end portion of the post or support 10 and form a pivot for the cover on which it may rotate. Here it will be noted that the fit of the pin 12 in the post 10 is such that when the cover 11 is in place the cover bears against the outer or upper end portion of the post and is held in a position spaced slightly outwardly or upwardly of the outer or free edge of the wall 9. This is most clearly shown in Fig. 3 from which figure it will be apparent that the cover may be rotated independent of the cup and with the pin 12 as its axis. If preferred the bearing may be at the lower end of the pin 12.

Carried by the cover 11 in eccentric relation to the pin 12 is a pencil sharpening means 13 comprising a body member 14 having a tapered socket therein and having a slot in its side wall leading to said socket and through which extends a sharpening blade 15 which may be removably secured to the body as by a screw 16. Extending upwardly or outwardly from the body member 14 is a hollow stem or neck portion 17 through which an end portion of a pencil may be inserted into the socket in the body. On inserting the end of a pencil into the socket in the body 14 and turning the sharpening member relative to the pencil or turning the pencil relative to the sharpening member the end portion of the pencil will be cut away at an angle and the pencil sharpened as will be understood.

The sharpening means 13 is as above suggested mounted on or carried by the cover

and to this end the neck portion 17 is enlarged intermediate its ends to provide a ball 18. Cover 11 is provided with an opening 19 the edges of which are somewhat undercut as shown in Fig. 5 and secured against the underside of the cover is a plate 20 having a perforation or opening registering with the opening 19 in the cover and with its edges cut at an angle as are the edges of the opening 19. However, it will be noted that the edges of the opening in the plate incline in a direction opposite to the direction of inclination of the edge of the opening 19 in the cover.

The plate 20 is secured to the cover 11 by any suitable means as by rivets 21 and the sharpening means 13 is mounted on the cover by having the ball portion 18 of the sharpening means disposed in the openings in the cover and plate 20. An inspection of Fig. 5 will clearly show that the upper edge of the opening 19 in the cover engages the ball above its center while the lower edge of the opening through the plate 20 engages the ball below its center. Therefore, the ball is securely mounted and the sharpening means 13 attached to the cover.

This mounting means as thus far described would permit the sharpening means to rotate and also rock relative the cover. The ability of the sharpening means to rock relative to the cover is an important feature of the invention and prevents breaking of the lead of the pencil by lateral cramping during the sharpening operation as will later appear. However, the sharpening means must be held against rotation about its own axis or relative to the cover and to this end means are provided to secure the sharpening means against independent rotation and at the same time permit it to rock in all directions relative to the cover. This means as here disclosed comprises a tongue or tit 22 carried by the plate 20 and loosely fitting in a slot 23 in the ball 18.

The body 7 may be provided with flutes or corrugations in or on the outer surface of its side wall 9 both to give the body a finished appearance and to provide a better grip when the body is being held in the hand during the operation of sharpening a pencil. From the drawing it will be apparent that the neck 17 extends at the upper side of the cover 11 when the cover is on the body 7 and when a pencil is to be sharpened it is but necessary to insert an end of the pencil through the hollow pin or neck 17 and into the tapered socket in the body 14 and to then rotate the cover with the pin 12 as an axis and using the pencil 25 as a crank. During this operation the pencil will be held against rotation about its own axis and the sharpening means will be rotated about the pencil and sharpen it.

65 Shavings from the pencil will be caught

in the cup 7 and the cup may be emptied at any time by lifting off the cover. To facilitate this last operation the cover is preferably of a diameter slightly greater than the diameter of the cup whereby the edge portions of the cover are easily engaged by the fingers. During the sharpening operation it is important that the sharpening means 13 be so mounted that it may rock sideways as suggested by the broken lines in Fig. 3 since otherwise the pencil is likely to be broken due to lateral cramping. With the present device it is possible to sharpen a pencil with one hand since the device may be disposed on or secured to any suitable support and a pencil inserted through the stem 17 and used as a crank for operating the device. It is not necessary to hold the pencil in one hand and turn a crank or the like with the other. If desired, the entire sharpener including the cup 7 may be held in one hand while with the other hand a pencil is inserted and used as a crank for operating the device during which operation the pencil is sharpened.

Having thus set forth the nature of my invention, what I claim is:

1. In a pencil sharpener, a case, a cover member rotatable on the case, a sharpening means including a tapered socket and an inclined blade extending into the socket, means mounting said sharpening means on the cover at the inner side thereof and against rotation relative thereto, and said cover having an opening therethrough to said tapered socket whereby on inserting a pencil into the socket and using the pencil as a crank to rotate the cover the sharpening means will be rotated about the pencil and sharpen it.

2. In a pencil sharpener, a case including bottom and side walls, a post arranged centrally of said bottom wall and extending outwardly therefrom to project slightly beyond the side wall of the case, said post hollow in its outer end portion, a cover, a pin on said cover and disposed in the hollow end portion of the post and rotatably mounting the cover relative to the case, a sharpening means including a tapered socket and an inclined blade extending into the socket, means mounting said sharpening means on the cover at the inner side thereof and against rotation relative thereto, and said cover having an opening therethrough to said tapered socket whereby on inserting a pencil into the socket and using the pencil as a crank to rotate the cover the sharpening means will be rotated about the pencil and sharpen it.

3. In a pencil sharpener, a case including bottom and side walls, a post arranged centrally of said bottom wall and extending outwardly therefrom, said post hollow in its outer end portion, a cover, a pin on said cover and disposed in the hollow end portion of the post and rotatably mounting the cover relative to the case, sharpening means including

5 a tapered socket and an inclined blade extending into the socket, means mounting said sharpening means on the cover at the inner side thereof for lateral rocking movement in all directions and against rotation relative to the cover, and said cover having an opening therethrough to said tapered socket whereby on inserting a pencil into the socket and using the pencil as a crank to rotate the cover the 10 sharpening means will be rotated about the pencil and sharpen it.

15 4. In a pencil sharpener, a cylindrical case including bottom and side walls, a post arranged centrally of said bottom wall and extending outwardly therefrom, said post hollow in its outer end portion, a cover, a pin on said cover and disposed in the hollow end portion of the post and rotatably mounting the cover relative to the case, sharpening 20 means including a tapered socket and an inclined blade extending into the socket, means mounting said sharpening means on the cover at the inner side thereof and against rotation relative thereto, said cover having an opening therethrough to said tapered socket whereby on inserting a pencil into the socket and using the pencil as a crank to rotate the cover the sharpening means will be rotated about the pencil and sharpen it, and said cover of 25 30 greater diameter than said case whereby its edge portions may be easily grasped to remove it from the case.

35 5. In a pencil sharpener, a case, a cover rotatable on the case, a sharpening means including a tapered socket and an inclined blade extending into the socket, means mounting said sharpening means for rocking movement in all directions on the cover at the inner side thereof and against rotation relative thereto, and said cover having an opening therethrough to said tapered socket whereby on inserting a pencil into the socket and using the pencil as a crank to rotate the cover the sharpening means will be rotated 40 about the pencil and sharpen it and will rock to prevent breaking of the lead of the pencil by lateral cramping thereof during the sharpening operation.

45 6. In a pencil sharpener, a case, a cover 50 rotatable on the case, a sharpening means including a tapered socket, an inclined blade extending into the socket, and a hollow stem leading to said socket, said cover having an opening therethrough eccentric to its axis of rotation, said sharpening means having its hollow stem extending through said opening in the cover, means mounting said hollow stem in said opening in the cover and against rotation therein, and said stem adapted to have a pencil inserted therethrough and into the socket whereby on using the pencil as a crank to rotate the cover the sharpening means will be rotated about the pencil and sharpen it.

55 7. In a pencil sharpener, a case, a cover rotatable on the case, a sharpening means including a tapered socket, an inclined blade extending into the socket, and a hollow stem leading to said socket, said cover having an opening therethrough eccentric to its axis of rotation, said sharpening means having its hollow stem extending through said opening in the cover, means mounting said hollow stem in said opening in the cover and against rotation therein, and said stem adapted to have a pencil inserted therethrough and into the socket whereby on using the pencil as a crank to rotate the cover the sharpening means will be rotated about the pencil and sharpen it.

60 8. In a pencil sharpener, a case, a cover rotatable on the case, a sharpening means including a tapered socket, an inclined blade extending into the socket, and a hollow stem leading to said socket, said cover having an opening therethrough eccentric to its axis of rotation, said sharpening means having its hollow stem extending through said opening in the cover, means mounting said hollow stem in said opening in the cover and against rotation therein, said stem adapted to have a pencil inserted therethrough and into the socket whereby on using the pencil as a crank to rotate the cover the sharpening means will be rotated about the pencil and sharpen it, and said mounting means mounting said stem for rocking movement relative to the cover to prevent breaking of the lead of the pencil by lateral cramping thereof during the sharpening operation.

65 9. In a pencil sharpener, a case, a cover rotatable on the case, a sharpening means including a member having a tapered socket therein, an inclined blade extending into the socket, and a hollow stem leading to said socket, said cover having an opening therethrough eccentric to its axis of rotation, said sharpening means having its hollow stem extending through said opening in the cover, means mounting said hollow stem in said opening in the cover, said mounting means including a ball rigid on the stem and engaged above its center by the edges of the opening, a perforated plate at the underside of the cover and engaging the ball below its center, complementary means on said ball and plate and securing the ball against rotation relative to the cover but permitting of rocking movement of the ball and thus the sharpening means, and said stem adapted to have a pencil inserted therethrough into the socket whereby on using the pencil as a crank to rotate the cover the sharpening means will be rotated about the pencil and sharpen it and the sharpening means will rock to prevent breaking of the lead of the pencil by lateral cramping thereof in the sharpening operation.

70 10. In a pencil sharpener, a case, a cover rotatable on the case, a sharpening means including a member having a tapered socket therein, an inclined blade extending into the socket, and a hollow stem leading to said socket, said cover having an opening therethrough eccentric to its axis of rotation, said sharpening means having its hollow stem extending through said opening in the cover, means mounting said hollow stem in said opening in the cover, said means including a ball rigid on the stem and engaged above its center by the edges of the opening, a perforated plate at the under side of the cover and engaging the ball below its center, said ball having a slot therein, a tongue on said plate and entering said slot whereby said ball and the sharpening means may rock relative to
